EDWARD J. BROCK, OF ST. LOUIS, MISSOURI

WATER PURIFIER

Application filed May 14, 1927. Serial No. 191,831.

This invention relates generally to water purifiers such as are used in conjunction with boilers for mechanically removing sediment and impurities from the feed water before introducing it into the boiler, and the invention has particular reference to a water purifier which may be used in conjunction with a water tube boiler as well as with horizontal boilers, and boilers of other types.

10 My improved purifier may also be used for purifying water to be passed through the water jackets of engines for cooling purposes.

The water purifier disclosed in the present application is an improvement on the water purifier disclosed in an application filed by me on May 22nd, 1926, Ser. No. 110,900. It was found in actual practice that though the apparatus disclosed in the pending application referred to was very well adapted for use with horizontal boilers and functioned with great efficiency when used with a boiler of this type, it could not be made to function efficiently when used in conjunction with water tube and other boilers of relatively great evaporating capacity, because of its limited capacity. The purifier disclosed in my pending application comprises a single elongated shell through which the water to be purified is passed, and while this shell may be of any desired length insofar as its operation is concerned, and consequently could be of enormous length to have sufficient capacity so that it may be associated with a water tube or other boiler having great evaporating capacity, still the length of the shell is limited by the dimensions of the boiler setting and of the boiler room in which it is contained. I have, therefore, devised the apparatus disclosed in the present application, which embodies the principles of the earlier invention but is elaborated and modified with relation thereto, so that the present apparatus is capable of very efficient operation with a water tube boiler.

15 The general objects of the present invention are the same as those in connection with the invention disclosed in my earlier application for patent referred to, to which attention is directed, and in addition to those objects, the predominant object of the present

invention is to produce a purifier embodying the principles of my earlier invention which will function with great efficiency in conjunction with a water tube or other boiler having relatively great evaporating capacity.

55 Figure 1 is a fragmentary plan view of my improved purifier associated with a water tube boiler, a part of the boiler being broken away to show the manner in which the purifier is connected to the boiler;

60 Figure 2 is a side elevation of the boiler and purifier shown in Fig. 1;

65 Figure 3 is an end elevation of the boiler and purifier shown in Figs. 1 and 2;

70 Figure 4 is an enlarged fragmentary sectional detail showing the manner in which the connection leading to one of the sediment discharge pipes within a shell of the purifier is extended through the wall of said shell;

75 Figure 5 is an enlarged fragmentary sectional detail showing the manner of extending one of the sediment discharge pipes through a wall of a shell of the purifier when said discharge pipe is extended through a head of said shell;

80 Figure 6 is a side elevation of a boiler provided with my improved purifier and illustrating a modified form of means for connecting the purifier to the boiler;

85 Figure 7 is an end elevation of the boiler and purifier shown in Fig. 6, parts of the boiler being broken away to show the means for connecting the purifier to the boiler;

90 Figure 8 is an enlarged sectional view taken on line 8—8 of Fig. 3;

95 Figure 9 is a horizontal section of the dome of the uppermost shell of the purifier looking upwardly and showing the blow-off pipe therein.

Referring now to the drawings, A designates a water tube boiler, the water tube boiler illustrated in the drawings being of the Stirling type, but it is obvious, of course, that the invention may be used with boilers of other types. The boiler A is provided with the usual walls and includes a plurality of steam drums B at the upper portion of the boiler and a mud drum C at the lower portion of said boiler. The mud drum C is connected 100

to the steam drums B by the usual tubes D (Fig. 3). The purifier, which is designated generally by the reference character P, comprises a plurality of elongated shells 1, said elongated shells 1 being preferably arranged one above the other and the longitudinal axis of each of said shells being supported in a substantially horizontal position below the water level of the boiler. The righthand end of the uppermost shell 1 is the inlet end of the purifier and receives water from the boiler through connections 2 which may be certain of the water tubes of the boiler which have been severed and the portions thereof associated with one of the steam drums B extended through a side wall of the boiler. It is obvious, however, when portions of severed tubes would not be the proper length, that said tubes may be removed entirely from the boiler and new tubes associated with said boiler to produce the connections 2. The connections 2 are in communication with a coupling 3 through which latter a feed water pipe 4 extends through the instrumentality of a communicating elongated pipe 5 which is bolted to and is in communication with the coupling 3 as shown in Fig. 2; said elongated pipe being closed at its outer end by a cap 6. At its lower end, the coupling is provided with a flange 8 which is bolted as at 9 to a casting 10 riveted on the top of the uppermost shell 1 near one end thereof (Fig. 8). The coupling 3 is provided with a throat 11 communicating with the pipe 5 and which extends through the flange 8 and communicates with an opening in the casting 10 which, in turn, communicates with an opening 12 in the top of the purifier shell. The lower side of the throat 11 extending from the end of the pipe 5 to the opening in the casting 10 is curved, as indicated at 13, which construction permits of the easy flow of the water from the boiler to the purifier without an abrupt change in its course, thereby reducing friction. The feed water pipe 4 extends to near the lower end of the throat 11, so that as the cold feed water is discharged from the lower end of this pipe, it tends to produce a siphon effect and to withdraw the hot water from the boiler and thus promote the circulation of the same with the cold water through the purifier. The throat 11 also affords a mixing chamber for the hot and cold water, and this construction also avoids an objection incident to certain prior constructions, in that in the latter, the outlet passage to the purifier shell would very frequently become clogged by deposits from the water entering through the pipe 4. In the construction described and shown in Fig. 8, a free passage of relatively large diameter is provided for the passage of the water into the purifier shell, and this passage will be automatically kept clean by the flow of the water into the shell. Further, the lower end of the pipe 4 extends to near

the opening 12 of the shell. This opening is preferably made of considerably larger diameter than the pipe 4 so that the feed water which contains most of the impurities will tend to pass directly from the pipe 4 into the purifier through said opening without affording opportunity for impurities therein to deposit on the wall of the throat. 70

The water passes from the throat 11 down into the uppermost shell and onto a longitudinally inclined baffle 15, which is preferably set at an angle of approximately 22° and which prevents the incoming water from agitating the water and sediment within the upper shell and also causes the water to have a 80 longer course of travel. On the bottom of the uppermost shell of the purifier, I preferably provide two baffles or baffle plates, the one indicated by the numeral 16 being located toward the feed end of the shell, and the 85 other, 17, being located centrally of the shell. These baffles tend to prevent or to interrupt circulation along the bottom of the uppermost shell of the purifier, so that the sediment will accumulate and deposit on said bottom. In order to discharge the sediment from the uppermost shell of the purifier, I provide two or more sediment discharge pipes 18 and 19, respectively, the discharge pipe 18 extending from a point adjacent to the baffle plate 17 to a point near the righthand end of the purifier shell, as shown in Fig. 1, and the discharge pipe 19 extending from a point adjacent to the baffle plate 17 to a point near the lefthand end of the purifier. Each of these sediment discharge pipes 18 and 19 is closed at its opposite ends by caps 20 and is provided along its bottom with perforations which will be referred to later herein. Each of these pipes is preferably 90 formed in two sections connected centrally to a T-coupling 21 and to these couplings are connected outlet pipes 22 and 23, respectively. The outlet pipes 22 and 23 are connected to downwardly inclined pipes 24 which are, in turn, connected at their lower ends, as shown in Fig. 2, to the main blow-off pipe 25; each of the outlet pipes 22 and 23 is provided with its individual valve 26 which enable the two sediment pipes to be blown out independently if desired. This arrangement permits the use of pipes of relatively small size, which are convenient and economical to operate, and also when the section of the purifier shell on one side of the baffle plate 17 is 100 blown out, this operation does not disturb the sediment in the other part of the purifier shell. 105

On the upper side of the uppermost shell of the purifier and projecting downwardly 115 into the interior thereof, preferably at an angle of approximately 47°, I provide a baffle plate 27 near the outlet end of the shell, which operates to retard the rate of circulation along the upper part of the shell and to 120

lengthen the path of the circulation. Between the baffle plate 27 and the end or head 28 of the shell, I provide an outlet stand pipe 29 having its mouth 30 disposed at an elevation within the shell; that is to say, the mouth 30 is very close to the upper wall of the shell, so that substantially only clear soft water will enter this stand pipe. The pipe 29 is vertical and is connected at its lower end to a tank flange 31 which is secured to the shell at the bottom thereof, said tank flange 31 being of such nature that a pressure-tight joint will be provided at this point.

The shell of the purifier, which is located immediately below the uppermost shell thereof, is provided with an opening in its wall at the top thereof which is in vertical alinement with the stand pipe 29 in said uppermost shell, and arranged adjacent to the opening in the lower shell is a tank flange 32 similar to the tank flange 31 already referred to. The tank flanges 31 and 32 are connected by means of a short section of pipe 33, whereby water which passes into the mouth 30 of the stand pipe 29 will pass into the intermediate shell of the purifier.

By reason of the presence and location of the baffle plate 27, an air pocket is formed in which air tends to accumulate in the vicinity of the mouth 30 of the pipe 29 and to stop the circulation in the purifier when the latter is first filled. In order to prevent this, I provide means for releasing any air which may accumulate at this point.

For this purpose, I provide a by-pass connection 34 which will operate to automatically release air from the vicinity of the mouth 30 to an air, oil and sediment trap 35 which I provide on the upper side of the uppermost shell of the purifier back of the baffle 27. The by-pass connection 34 is connected to the shell above the top of the stand pipe 29 and communicates with the trap 35 through the side thereof at a point preferably about midway of its height. The trap 35, due to the high temperature in the shell, operates to trap any air, oil or sediment moving along the upper side of the shell, as will be understood. In order to provide for releasing air which may accumulate in this trap, I provide a line of piping 36 which is in communication with the interior of the trap 35 at the top thereof and communicates at its opposite end with one of the steam drums B at the upper portion of the boiler. Also, if desired, the piping 36 may lead to the steam pipe leading from the boiler, or the trap 35 may be provided with an automatically-operated valve for releasing the air therein, as shown in my pending application.

The sediment pipes 18 and 19 are provided, as previously stated, with perforations, and these perforations are preferably located on the underside only of the pipes and extend throughout their length. When either or

both of the valves 26 are opened, the pressure existing within the upper shell of the purifier will force sediment out through the perforations in the sediment pipes and through their outlet connections. According to this invention, the size of the openings in the pipes 18 and 19 is such that their total area will equal the area of the outlet pipes 22 and 23, allowance being made also for friction.

In practice, it is found that most of the sediment accumulates in the inlet end of the shell, and, therefore, the outlet connection 22 must be opened much more frequently than the outlet connection 23. The baffle plate 17 facilitates the operation of blowing out one end of the shell as it tends to prevent disturbance of the sediment in the opposite end. This baffle 17, therefore, performs a function in this respect in addition to its other function of tending to facilitate the deposit of sediment in the inlet end of the shell. The baffle 18 directs the circulation to the top of the shell and to a large extent prevents the sediment in the bottom of the shell from being stirred up, and affords, therefore, a quiet zone and ample space in which impurities may settle out of the water in the path of circulation. The baffle 27, of course, prevents the direct flow of water along the top of the shell through the mouth 30 of the stand pipe 29 and by directing the circulation downward, tends to cause the impurities, which are heavier than the water, to pass to and settle on the bottom of the shell so that only relatively pure water will rise and pass into the mouth 30.

The surface of the water in the trap 35 will, after a time, be covered with scum, oil and the like, and in order to remove this, I provide a surface blow-off which is illustrated clearly in Fig. 2. This blow-off is in the form of a pipe 40 which, at one end as shown in Fig. 2, is connected to the angularly arranged blow-off pipe 24, associated with the sediment discharge pipe 19, at a point below the valve 26. At its upper end, this pipe 40 has a horizontal extension entering the side of the trap 35, and said pipe is preferably bent to substantially encircle the interior of said trap and is provided at its outer end with a cap 41. The circular portion of this blow-off pipe within the trap is indicated by the numeral 42 and its underside is provided with a series of perforations 43 which preferably decrease in diameter, as shown, from the outer end containing the cap 41 to the entrance point of the pipe 40. The total area of the apertures 43 is made to equal the area of the pipe 40, allowance being made for friction, and in this way all of the apertures in the blow-off portion 42 are effective in removing scum from the surface of the water in the trap. The pipe 40 is provided with a valve 44 substantially at the point where said pipe is con-

nected to the blow-off pipe 24, whereby passage of matter through said blow-off pipe may be controlled, and it is obvious, of course, that the blowing-off action occurs whenever 5 said valve 44 is opened.

The shell 1 of the purifier P, or the shell which I have previously referred to as the intermediate shell, is a duplicate of the uppermost shell already described in detail, with 10 the exception that insofar as the positions of the various baffles and the stand pipe located therein are concerned, the intermediate shell is arranged with ends reversed with respect to the uppermost shell. Located within the 15 intermediate shell at the lefthand or feed end thereof is a longitudinally-inclined baffle 45 arranged preferably at an angle of approximately 22°, which baffle corresponds to the baffle 15 in the uppermost shell, said baffle 20 45 being intended to prevent incoming water from agitating the water and sediment within said intermediate shell. The intermediate shell is also provided with a baffle 46 at the feed end thereof and a baffle 47 located centrally of the shell, which baffles tend to prevent or interrupt circulation along the bottom of the shell so that sediment will accumulate and deposit on said bottom.

In order to discharge the sediment from 30 the intermediate shell of the purifier, I provide two or more sediment discharge pipes 48 and 49, respectively, the discharge pipe 48 extending from a point adjacent to the baffle 47 to a point near the lefthand end of 35 the shell, and the discharge pipe 49 extending from a point adjacent to said baffle 47 to a point near the righthand end of the shell. Each of these sediment discharge pipes is closed at its opposite ends by caps 40 50 and is provided along its bottom with perforations. As in the case of the sediment discharge pipes associated with the uppermost shell, each of the sediment discharge pipes 48 and 49 is preferably formed in two 45 sections connected centrally to a T-coupling, and to these couplings are connected outlet pipes 51 and 52, respectively. The outlet pipes 51 and 52 are connected to downwardly inclined pipes 53 which are, in turn, connected at their lower ends as shown in Fig. 2 to the main blow-off pipe 25. Also, each 50 of the outlet pipes 51 and 52 is provided with its individual valve 54 which enables the two sediment pipes to be blown out independently if desired. In the upper portion of the intermediate shell at the discharge end thereof, I provide a baffle plate 55 which, as in the case of the baffle 27 in the upper shell, is arranged preferably at an angle of approximately 47°, said baffle being intended to retard the rate of circulation along the upper part of the shell and to lengthen the path of circulation. Between the baffle plate 55 and the righthand end of the shell, I provide an outlet stand pipe 56 having its mouth

57 disposed at an elevation within the shell so that substantially only clear soft water will enter this stand pipe. The pipe 56 is vertical and is connected at its lower end to a tank flange 56' which is secured to the 70 shell at the bottom thereof in such manner as to provide a pressure-tight joint at this point.

The lowermost shell of the purifier is provided with an opening in its wall at the top thereof which is in vertical alinement with the stand pipe 56 of the intermediate shell, and arranged adjacent to the opening in the wall of the lowermost shell is a tank flange 58 similar to the tank flange 56' already referred to. The tank flanges 56' and 58 are connected by means of a short section of pipe 59 whereby water which passes into the mouth 57 of the stand pipe 56 within the intermediate shell will pass into the lowermost shell of the purifier.

The lowermost shell of the purifier is a duplicate of the uppermost shell and of the intermediate shell of the purifier with the exception that, insofar as the positions of the baffles and stand pipe of the lowermost shell are concerned, said lowermost shell is arranged with ends reversed with respect to the intermediate shell.

The water passing into the lowermost shell 55 from the intermediate shell contacts with a longitudinally-inclined baffle 60 which is preferably set at an angle of approximately 22°, this baffle, as is the case in connection with the baffles 45 and 15, being intended to prevent the incoming water from agitating the water and sediment within the lowermost shell, and said baffle 60 also causes the incoming water to have a longer course of travel. On the bottom of the lowermost shell, I provide two baffles or baffle plates 61 and 62, located adjacent to the feed end and centrally of the shell, respectively. These baffles tend to prevent or to interrupt circulation along the bottom of the lowermost shell of the purifier, so that the sediment will accumulate and deposit on said bottom. The lowermost shell is also provided with two or more sediment discharge pipes 63 and 64, the discharge pipe 63 extending from a point adjacent to the baffle 62 to a point near the righthand end of the purifier shell, and the discharge pipe 64 extending from a point adjacent to said baffle plate 62 to a point near the lefthand end of the shell. Each of these sediment discharge pipes 63 and 64 is closed at its opposite ends by caps 65 and is provided along its bottom with perforations. Each of these pipes is preferably formed in two sections connected centrally to a T-coupling, and to these couplings are connected outlet pipes 66 and 67, respectively. The outlet pipes 66 and 67 are connected to downwardly inclined pipes 68 which are, in turn, connected at their lower ends as shown 120

in Fig. 2, to the main blow-off pipe 25. Each of the outlet pipes 66 and 67 is provided with its individual valve 69 which enable the two sediment pipes to be blown out independently if desired.

In the upper portion of the lowermost shell at the discharge end thereof is a baffle plate 70 which inclines downwardly into the interior of the shell, preferably at an angle of approximately 47°. This baffle plate operates to retard circulation along the upper part of the shell and to lengthen the path of circulation. Between the baffle plate 70 and the adjacent end of the shell, I provide an outlet stand pipe 71 having its mouth 72 disposed at an elevation within the shell so that substantially only clear soft water will enter this stand pipe. The stand pipe 71 is arranged vertically and extends through an opening in the wall of the shell at the bottom thereof, and said stand pipe is connected at its lower end to a tank flange 73 which is secured to the shell so as to provide a pressure-tight joint at this point. 74 designates an elbow, or other suitable connection, which is in communication with the stand pipe 71 and is secured to the tank flange 73, said elbow 74 being connected by means of bolts or otherwise to a pipe 75 which extends longitudinally of the lowermost shell of the purifier at a point immediately below said lowermost shell. At the end thereof remote from the end of the pipe 75 which is connected to the elbow 74, said pipe is provided with a cap 76 by means of which said end of said pipe is closed.

To connect the discharge end of the purifier to the boiler, I employ tubes which may be portions of the water tubes which were severed to provide the inlet connections 2 and which tube portions are associated with the mud drum of the boiler. These tube portions, which are designated by the reference character 77 in the drawings, are extended through a wall of the boiler and connect the mud drum C of the boiler with the elongated pipe 75. Also as in the case of the connections 2, separate tubes may be employed instead of using parts of water tubes of the boiler, if desired. In this manner, water which passes through the pipe 75 will pass into and through the tube portions 77 and into the mud drum of the boiler. The area of the pipe 75 approximately equals the area of all of the connections 77, allowance being made for friction.

To provide for releasing air which may accumulate in the air pockets produced adjacent to the open upper ends of the stand pipes in the intermediate and lower shells by the presence of the baffle plates 45 and 70 in the respective shells, I associate with each of said shells an air by-pass. The by-pass associated with the intermediate shell comprises a pipe 78 which is connected to said intermediate

shell above the stand pipe 56 and extends longitudinally of said intermediate shell to a point beyond the lefthand end thereof (Fig. 2). Likewise, the by-pass associated with the lowermost shell comprises a pipe 79 connected to said lowermost shell above the stand pipe 71 and extends beyond the lefthand end of said shell. The pipes 78 and 79 are connected to a pipe 80 which connects to and communicates with the pipe 36 leading from the trap 35 of the uppermost shell to one of the steam drums of the boiler. In view of this arrangement, it is obvious that air will be conducted from the vicinity of the mouths of the stand pipes in the two lower shells, whereby air traps at these points are avoided.

In the operation of my improved purifier, it is plain that feed water will pass longitudinally through the successive shells, depositing any impurities and sediment that may be contained in said feed water on the bottoms of the shells so that when said water finally passes into the mud drum of the boiler, it will be free from impurities and sediment. This action is due to the high temperature within the shells comprising the purifier, which temperature, however, is a few degrees under boiling temperature, so that no boiling takes place in the purifier. Also, because the purifier is not subjected to heat of flames, the sediment therein will not be baked into a scale. Likewise, the heating of the feed water as it passes through the purifier equalizes the temperature between the feed water and the boiler water in that said feed water enters the boiler at practically boiler temperature. It is likewise plain that each shell may be individually blown out so as to discharge the sediment therefrom, and further, that the opposite ends of each shell may be independently blown out.

When the valve 44 is opened to discharge scum, oil and the like from the trap 35, the valve 36 associated with the pipe 36 leading from said trap to one of the steam drums will be closed to prevent withdrawal of steam from said steam drum.

In the modified form of the invention shown in Figs. 6 and 7, I do not utilize portions of certain of the water tubes of the boiler as inlet and discharge connections of the purifier. In accordance with this form of the invention, I employ a separate inlet connection 85 which is connected to one of the steam drums of the boiler below the water lever and with the coupling 3, as shown clearly in Fig. 7, and also I employ a separate discharge connection 86 which is connected to the mud drum of the boiler and to an elbow 87 which, in turn, is arranged in communication with the stand pipe 71 of the lowermost shell of the purifier by a pipe 88.

Also, as suggested by Fig. 5, I may extend the sediment discharge pipes through the

ends or heads of the shells instead of through the sides thereof as in the preferred construction of the invention. In the view referred to, 1' designates a shell of the purifier through the end wall or head 1^a of which a sediment discharge pipe 18' is extended, which sediment discharge pipe will be connected in any convenient manner to the main blow-off pipe.

It will be noted by referring to Fig. 2 that between the uppermost and the intermediate shells of the purifier at the righthand end thereof, I provide a pair of tank flanges 90 into which a short section of pipe 91 is screwed. This arrangement resembles the connection between the uppermost and intermediate shells at the opposite ends of said shells through which the interiors of these shells are placed in communication with each other. However, the tank flanges 90 and pipe 91 do not act as connections between the interiors of the shells referred to, for the reason that the walls of said shells are not apertured at this point, said elements merely acting as supporting means for the uppermost shell at the righthand end thereof. In this connection, it is pointed out that one of the tank flanges 90 will be secured to the intermediate shell of the purifier, but the other tank flange 90 will not be secured to the uppermost shell but merely provides a seat for said shell. In view of this arrangement, the shells are capable of independent movement longitudinally when subjected to expansion and contraction due to change in temperature.

At the lefthand end of the purifier and between the intermediate and the lowermost shells, I provide a pair of tank flanges 92 and a short section of pipe 93 similar to the elements 90 and 91 just referred to. The tank flanges 92 and short section of pipe 93 provide means for supporting the intermediate shell at the lefthand end thereof, the walls of said shells being imperforate at said supporting means so that there will be no communication between the shells through the section of pipe 93. In this case also, only one of the tank flanges is connected to a shell so that said shells may expand and contract longitudinally with relation to each other.

I prefer to enclose the plurality of shells of which one of my improved purifiers is composed, within a casing 95 formed preferably of sheet metal from which the opposite end portions of the shells extend, which casing is supported by a suitable frame 96. Also, I prefer to interpose suitable heat insulating material 97 between the walls of the casing 95 and the walls of the shells of the purifier, as indicated in Figs. 2 and 4.

It is obvious, of course, that instead of producing a purifier composed of a plurality of separate shells as in the preferred construction of my invention, I may produce a puri-

fier which comprises a single shell of proper capacity through which a plurality of passageways are formed in any desired relative arrangement, which passageways will be provided with the baffles, stand pipes, and sediment discharge pipes as disclosed in connection with my preferred construction.

The shells of which the purifier is composed are each set at an incline so that its outlet end is slightly higher than the inlet end thereof, in order to facilitate the passage of air along the tops of the shells to points where said air may pass from the shells through the air conductors 34, 78, 79 and 80. The scale of the drawing relative to the actual size of the purifier is very small, and as the inclination is very slight, such inclination would scarcely be perceptible to the eye, and no attempt has been made to illustrate it. I desire to state the fact, however, in the interest of a full disclosure of the invention.

The advantage of the preferred form of the invention, which involves withdrawing boiler water from the boiler at points distributed lengthwise, or transversely, of the boiler, and introducing water into the boiler at points similarly distributed, is of great importance inasmuch as this arrangement results in increased circulation of the water throughout the entire boiler. This arrangement eliminates the likelihood that circulation would be increased in a portion only of the boiler, as may be the case if a single connection were employed as in my pending application, which would result in differences of temperature of the boiler water, whereby harm may result to the boiler due to expansion and contraction thereof.

I claim:

1. In a water purifier of the class described, the combination of a plurality of elongated shells arranged one above the other, the topmost shell and each intermediate shell having an outlet pipe at one end thereof communicating with the corresponding end of a succeeding shell and having its inlet mouth located at an elevated level within its shell, said outlet pipes being arranged at opposite ends of alternate shells and the outlet pipe from the lowermost shell leading to the boiler, each of said shells being inclined upwardly toward its outlet end, means for removing the sediment from said shells, and an air release pipe leading out of the upper side of each shell at the end portion thereof containing the outlet pipe.

2. In a water purifier of the class described, the combination of a plurality of elongated shells arranged one above the other in a substantially horizontal position and in communication with each other, a connection including a feed water pipe at an end and upper side of the topmost of said shells adapted to be connected with a boiler to introduce a mixture of hot boiler water and feed water

into the purifier, an outlet pipe leading from an end of the lowermost of said elongated shells into the boiler, means for removing sediment from said shells, and supporting members for said shells arranged intermediate of each pair of shells and mounted at opposite ends of alternate shells, one end of each shell being loosely supported on the supporting member mounted on the shell beneath it, whereby said shells may expand and contract relative to each other.

3. In a water purifier of the class described, the combination of a plurality of elongated shells arranged one above the other in substantially horizontal position and in communication with each other at opposite ends in alternation, a connection including a feed water pipe at an end and upper side of the topmost of said shells adapted to be connected with a boiler to introduce a mixture of boiler water and feed water into said shell, an outlet pipe leading from an end of the lowermost of said shells into the boiler, a blow-off system common to all of the shells, a dome extended upwardly from one of said shells and operating as a trap in which air from the upper portion of said shell is collected, and a pipe for placing said blow-off system in communication with the interior of said dome.

In testimony whereof, I have hereunto set my hand.

EDWARD J. BROCK.
